FLOOD LAMP

Hy Hilzen, 40 Gateway Road,
Yonkers, N.Y. 10703

Filed Sept. 6, 1968, Ser. No. 13,433

Term of patent 14 years

Int. Cl. D26—02

U.S. Cl. D48—20

FIG. 1 is a perspective view of a flood lamp showing my new design, as viewed from the rear thereof;

FIG. 2 is a side view thereof; both sides being identical;

FIG. 3 is a rear view thereof;

FIG. 4 is a top plan view of FIG. 1, and the bottom view thereof also.

The interior surface of the lamp's reflector shield follows the profile of the outer shell and terminates in a conventional socket member.

The support member is shown in broken lines in FIG. 3 for illustrative purposes only.

I claim:

The ornamental design for a flood lamp, substantially as shown and described.
